UNITED STATES PATENT OFFICE.

THEODORE C. PROUTY, OF ELGIN, ILLINOIS, ASSIGNOR, BY MESNE ASSIGNMENTS, TO PATENTS HOLDING CORPORATION, OF CHICAGO, ILLINOIS, A CORPORATION OF DELAWARE.

NEEDLE VALVE.

Application filed April 2, 1919. Serial No. 286,986.

To all whom it may concern:

Be it known that I, THEODORE C. PROUTY, a citizen of the United States, residing at Elgin, in the county of Kane and State of Illinois, have invented certain new and useful Improvements in Needle Valves, of which the following is a specification.

My invention relates to certain new and useful improvements in needle valves for valve mechanisms which are used in connection with gas supply apparatus where delicate control is desirable, particularly in connection with pulmotors and oxygenizing apparatus for aviators, and the like.

The invention consists in the features, combinations, and details of construction hereinafter described and claimed.

In disclosing my invention, so that those skilled in the art may practice the same, I have chosen to illustrate it in combination with one type of reducing valve mechanism, such as may be used in connection with oxygenizing apparatus for aviators. It will be understood, however, that I do not desire to limit the use of my invention to such devices, or any more than is pointed out in the accompanying claims.

It is well known that in the art to which this invention relates nearly all gases, as well as atmospheric air, contain more or less solid materials in a finely divided state, so that when such gases are forced through delicate valves under high pressures, or velocities, a scoring action is likely to, and in most cases does, take place on the tapered end of the needle valve against which end such solids are impinged at a high velocity. Again, where oils or glycerine are present in the gas or air a gumming action results, all of which impair the efficiency of such valves and, in connection with oxygenizing devices for aviation purposes, render such valves practically useless.

Further, it will be apparent that if any moisture is present in the air or gas and the valve is used as an oxygenizing apparatus for aviators, such moisture at high altitudes would freeze and the resulting frost or ice would impede the correct operation and proper functioning of the valve with possible fatal results.

In the accompanying drawings—

Figure 1 is a sectional elevation of one type of reducing valve, showing my improved needle valve in operating position;

Fig. 2 is a cross sectional elevation, taken on the line 2—2 of Fig. 3, showing the interior of the valve;

Fig. 3 is a cross sectional elevation, taken on the line 3—3 of Fig. 2; and

Fig. 4 is a perspective view of the jewelled needle valve.

In disclosing my invention I have, as above stated, chosen to disclose it in connection with the reducing valve of a certain type, that is, a reducing valve which may be used in connection with oxygenizing apparatus. The valve mechanism, generally speaking, is preferably formed of a cup-shaped body portion 4, provided with a low pressure gas chamber 5. A yoke, block, or similar element 6 is provided and rigidly secured to the body portion of the valve mechanism in the gas chamber thereof by means of its threaded stems 7 and locking nuts 8. This yoke or block to all intents and practical purposes forms a part of the body portion, and is provided with an inlet port 9 and an outlet port 10, which may be connected with any desired mechanism.

A cup-shaped cap portion 11 is provided, which has threaded engagement with the body portion, as shown, and forms a diaphragm 12, which, in turn, is operatively connected with a valve-carrying bar 13, upon which a jewelled needle valve 14 is mounted, and by which it is operated to open and close the valved opening 18 of the inlet port 9. The jewelled needle valve is preferably made of sapphire, cut and ground to the desired conical shape, and forms the said controlling valve. It is mounted upon the carrying bar, so that the diaphragm, which forms one of the walls of said gas chamber, at normal pressure holds said controlling valve in its normal open position, but when subjected to an excess of pressure it is extended or expanded so as to move the jewelled needle valve through its connecting mechanism to its closed position. The valve-carrying bar may be connected directly with the diaphragm portion, or, as shown in Fig. 3, may be connected by means of screws 17 with a flexible disk 15, the latter being connected by means of the threaded stem 16 with the diaphragm.

In operation, gas under pressure, such as oxygen, is supplied from any desired source, and enters the valve mechanism through the inlet port, passing through the valve open-

ing thereof into the low pressure chamber. When the gas pressure exceeds a predetermined amount, say, about fifty pounds to the square inch, the diaphragm is extended to 5 the right, and carries with it the valve-carrying bar and controlling valve, thereby closing the valve port. Such gas as may be in the reducing chamber will pass out through the outlet port, and when a sufficient amount 10 has passed out therethrough the pressure therein is reduced or falls below a predetermined amount, and the diaphragm is permitted to move inwardly, or in the opposite direction to its normal position, and returns 15 the jewelled needle to its initial or normal open position.

I claim:—

1. In an apparatus of the class described, a valve mechanism comprising a body portion provided with a valve port, a controlling sapphire needle valve for opening and closing the valve port, and means for operating said controlling needle valve.
2. In an apparatus of the class described, 25 a valve mechanism comprising a body portion providing a gas chamber, an element secured thereto so as to practically form a part thereof provided with a valve port, a controlling needle valve formed of a cone-shaped sapphire for opening and closing the valve port, and means for operating said controlling valve.
3. In an apparatus of the class described, 30 a valve mechanism comprising a body portion provided with a gas chamber, an element secured thereto so as to practically form a part of said body portion and provided with a valve port, a controlling sapphire needle valve for opening and closing said valve port, and a diaphragm element 35 forming one of the walls of said gas chamber and operatively connected with said controlling needle valve and arranged to be operated by fluid pressure.
4. In an apparatus of the class described, 40 a valve mechanism comprising a body portion provided with a gas-reducing chamber, a yoke or similar element secured thereto so as to practically form a part of said body portion and provided with a valve inlet port, a controlling sapphire needle valve for opening and closing said valve inlet port, a diaphragm element 45 forming the outer wall of said gas chamber and arranged to be operated by gas pressure, and a disk operatively connected with said controlling needle valve and said diaphragm.
5. In an apparatus of the class described, 50 a valve mechanism comprising a body portion provided with a valve port; a needle valve of dense, hard non-metallic, non-corrodible, non-silicious material for opening and closing the valve port; and means for operating said needle valve.
6. In an apparatus of the class described; 55

a valve mechanism comprising a body portion providing a gas chamber; an element secured thereto so as to practically form a part thereof provided with a valve port; a needle valve of dense, hard, non-corrodible, 70 non-silicious material having a tapered, cone-shaped end for opening and closing the valve port; and means for operating said needle valve.

7. In an apparatus of the class described; 75 a valve mechanism comprising a body portion provided with a gas chamber; an element secured thereto so as to practically form a part of said body portion and provided with a valve port; a needle valve of dense, hard, non-corrodible, non-silicious material for opening and closing said valve port; and a diaphragm element forming one of the walls of said gas chamber and operatively connected with said needle valve and arranged to be operated by fluid pressure.

8. In an apparatus of the class described; 80 a valve mechanism comprising a body portion provided with a gas reducing chamber; a yoke or similar element secured thereto so as to practically form a part of said body portion and provided with a valve port; a needle valve of dense, hard, non-corrodible, 90 non-silicious material for opening and closing said valve port; a diaphragm element forming the outer wall of said gas chamber and arranged to be operated by gas pressure; and a disc operatively connected with said needle valve and said diaphragm.

9. In an apparatus of the class described; 100 a valve mechanism comprising a body portion provided with a valve port; a needle valve of non-silicious lapideous material for opening and closing the valve port; and means for controlling said needle valve.

10. In an apparatus of the class described; 105 a valve mechanism comprising a body portion provided with a gas chamber; an element secured thereto so as to practically form a part thereof provided with a valve port; a needle valve formed of non-silicious lapideous material in the shape of a cone for opening and closing the valve port and means for operating said needle valve.

11. In an apparatus of the class described; 110 a valve mechanism comprising a body portion provided with a gas chamber; an element secured thereto so as to practically form a part of said body portion and provided with a valve port; a needle valve formed of non-silicious lapideous material for opening and closing said valve port; and a diaphragm element forming one of the walls of said gas chamber and operatively connected with said needle valve and arranged to be operated by fluid pressure.

12. In an apparatus of the class described; 115 a valve mechanism comprising a body portion provided with a gas reducing 120

chamber; a yoke or similar element secured thereto so as to practically form a part of said body portion and provided with a valve port; a controlling needle valve 5 formed of non-silicious lapideous material for opening and closing said valve port; a diaphragm element forming the inner wall of said gas chamber and arranged to be operated by gas pressure; and a disc operatively connected with said needle valve 10 and said diaphragm. In testimony whereof, I have subscribed my name.

THEODORE C. PROUTY.
